UNITED STATES PATENT OFFICE.

MICHAEL J. REILLY, OF CHICAGO, ILLINOIS.

IRONING-MACHINE.

1,171,248.

Specification of Letters Patent.

Patented Feb. 8, 1916.

Application filed March 3, 1913. Serial No. 751,942.

To all whom it may concern:

Be it known that I, MICHAEL J. REILLY, a citizen of the United States, and a resident of the city of Chicago, county of Cook, and State of Illinois, have invented certain new and useful Improvements in Ironing-Machines, of which the following is a specification.

My invention relates to improvements in ironing machines and has for its object the provision of a machine of this character which is of improved construction and operation and especially adapted for use in ironing corsets.

The invention consists in the combinations and arrangements of parts hereinafter described and claimed.

The invention will be best understood by reference to the accompanying drawings forming a part of this specification, and in which,

Figure 1 is a vertical section of an ironing machine embodying my invention, Fig. 2 is a section taken on line $x-x$ of Fig. 1, Fig. 3, 25 a section taken on line $y-y$ of Fig. 1, Fig. 4, a section taken on line $z-z$ of Fig. 1, Fig. 5, a section taken on line $v-v$ of Fig. 1, Fig. 6, a plan view of an ironing table employed in the machine, and Fig. 7, a section taken on 30 line $w-w$ of Fig. 5.

The preferred form of construction as illustrated in the accompanying drawings comprises a suitable hollow supporting frame or pedestal 1, upon which is mounted a laterally reciprocating support 2, said support being provided with a depending rack bar 3, provided with a suitable guide head 4 slidable in frame 1. Supporting member 2 is provided with a transverse T-slot 5 and an ironing table 6 is arranged on top of supporting member 2 and is provided with a cylindrical headed stud 7 operating in slot 5 to permit of adjustments of ironing table 6 both forwardly and backwardly and angularly.

An operating shaft 8 is arranged in a horizontally extending arm of frame 1 in operative relation with rack bar 3 and is provided at one end with a gear 9 meshing with rack bar 3. The other end of shaft 8 is provided with a gear 10 which meshes with a reciprocating rack bar 11 operated by a link 11' from crank shaft 12, controlled by tight and loose pulleys 12' in the usual manner. Shaft 12 carries a bevel gear 13 meshing with a bevel gear 14 secured to the lower end of a

vertical shaft 15 suitably mounted in frame 1. At its upper end shaft 15 is provided with a bevel gear 16 meshing with a bevel gear 17 on a counter-shaft 18 suitably mounted in frame 1. Shaft 18 also carries a bevel gear 19 meshing with a bevel gear 20 which is splined or feathered to a vertically reciprocating hollow shaft 21 suitably mounted in frame 1. Shaft 21 carries at its lower end a hollow ironing head 22 which is provided in its top with perforations 23 to permit the escape of burnt gases therefrom. A gas supply pipe 24 is arranged in shaft 21 and carries at its upper end a supporting head 25 which in turn carries a set screw 26 operating in an annular groove 27 in a collar 28 secured to the upper end of shaft 21, such construction constituting a swiveling support for pipe 24 in shaft 21 which permits 25 of rotation of shaft 21 while pipe 24 remains stationary. At its lower end shaft 21 carries a hollow burner 29 provided in its bottom with openings 30 for escape of gas therefrom, and pipe 24 is provided at its upper end with any suitable flexible connection for supplying gas thereto. By this arrangement it will be observed that the burner 29 may be held from rotation and permitted to reciprocate vertically while gas is supplied 35 thereto for heating ironing head 22. While this constitutes a simple and efficient means for heating the ironing head, other means such as an electric rheostat or coil may be substituted for the same purpose. 90

A ring 31 is mounted upon shaft 21 between two collars 32 which are secured to said shaft by means of suitable set screws. Ring 31 is provided with laterally extending pins 33 engaging slots 34 in the sides of a 95 fork 35 formed at the end of a lever 36 mounted in frame 1. The other end of lever 36 is connected by means of a link 37 to a treadle lever 38 as shown. By this arrangement it will be observed that shaft 21 and 100 consequently ironing head 22 may be readily depressed into contact with a corset or other article resting upon ironing table 6, and that the reciprocations of said ironing table and the manual adjustment thereof will permit 105 of the ready ironing of an article on said table.

While I have illustrated and described the preferred form of construction for carrying my invention into effect, this is capable of 110 variation and modification without departing from the spirit of the invention. I,

therefore, do not wish to be limited to the precise details of construction set forth, but desire to avail myself of such variations and modifications as come within the scope of the 5 appended claims.

Having described my invention what I claim as new and desire to secure by Letters Patent is:

1. An ironing machine comprising a hollow pedestal; a driving shaft located in the lower portion of said pedestal; a vertically reciprocatory rack bar in said pedestal; an operative connection between said shaft and rack bar; a shaft and two gears thereon, one 10 of said gears meshing with said rack; a reciprocatory support and a rack bar thereon meshing with said other gear; and an ironing member above and coöperating with said support, substantially as described.
2. An ironing machine comprising a hollow pedestal; a driving shaft located in the lower portion of said pedestal; a vertical shaft in said pedestal having a bevel gear connection with said shaft; a horizontal 15 shaft having a bevel gear connection with said vertical shaft; a rotating ironing member having a bevel gear connection with said horizontal shaft; a reciprocatory table co-operating with said ironing member; and an operative connection between said table and said driving shaft, substantially as described.
3. An ironing machine comprising a frame; a laterally reciprocatory support mounted in said frame and carrying a rack bar; a manually movable ironing table mounted upon the top of said support; an operating shaft in said frame in operative 20 relation with said rack bar; a gear on said shaft meshing with said rack bar; a second gear on said shaft; a reciprocatory rack bar meshing with said second gear; a vertically reciprocatory hollow shaft arranged over said ironing table; a hollow ironing member secured to the lower end of said hollow shaft; means for rotating said hollow shaft; means for reciprocating said hollow shaft vertically; a vertically reciprocatory gas supply pipe in said hollow shaft; and a burner at the lower end of said pipe for heating said ironing member, substantially as described.
4. An ironing machine comprising a frame; a laterally reciprocatory support mounted in said frame and carrying a depending rack bar; a manually movable ironing table mounted upon the top of said support; an operating shaft in said frame in operative 25 relation with said rack bar; a gear on said shaft meshing with said rack bar; a second gear on said shaft; a reciprocatory rack bar meshing with said second gear; a vertically reciprocatory hollow shaft arranged over said ironing table; a hollow ironing member secured to the lower end of said hollow shaft; means for rotating said hollow shaft; means for reciprocating said hollow shaft vertically; a vertically reciprocatory gas supply pipe in said hollow shaft; and a burner at the lower end of said pipe for heating said ironing member, substantially as described.
5. An ironing machine comprising a hollow vertically extending pedestal having two hollow horizontally extending arms arranged one above the other; a reciprocatory ironing table on the lower arm; an ironing member on the upper arm coöperating with said table; and means in said hollow pedestal and arms for operating said table and ironing member, substantially as described.

operative relation with said rack bar; a gear on said shaft meshing with said rack bar; a second gear on said shaft; a reciprocating rack bar meshing with said second gear; a vertically reciprocatory hollow shaft arranged over said ironing table; a hollow ironing member secured to the lower end of said hollow shaft; means for rotating said hollow shaft; means for reciprocating said hollow shaft vertically; a vertically reciprocatory gas supply pipe in said hollow shaft; and a burner at the lower end of said pipe for heating said ironing member, substantially as described.

5. An ironing machine comprising a frame; a laterally reciprocatory support mounted in said frame and carrying a depending rack bar; a manually movable ironing table mounted upon the top of said support, said ironing table having a T-slot and a headed stud connection with said support; an operating shaft in said frame in operative relation with said rack bar; a gear on said shaft meshing with said rack bar; a second gear on said shaft; a reciprocating rack bar meshing with said second gear; a vertically reciprocatory hollow shaft arranged over said ironing table; a hollow ironing member secured to the lower end of said hollow shaft; means for rotating said hollow shaft; means for reciprocating said hollow shaft vertically; a vertically reciprocatory gas supply pipe in said hollow shaft; and a burner at the lower end of said pipe for heating said ironing member, substantially as described.

6. An ironing machine comprising a hollow vertically extending pedestal having two hollow horizontally extending arms arranged one above the other; a reciprocatory ironing table on the lower arm; an ironing member on the upper arm coöperating with said table; and means in said hollow pedestal and arms for operating said table and ironing member, substantially as described.

In testimony whereof I have signed my name to this specification in the presence of two subscribing witnesses.

MICHAEL J. REILLY.
